DRIP MOLDING TRIM OR THE LIKE

Alva Gauthier, 1323 Channing St.,
Los Angeles, Calif.

Filed June 22, 1964, Ser. No. 80,505

Term of patent 14 years

(Cl. D13—6)

FIG. 1 is a front perspective view of a drip molding trim or the like embodying my new design;

FIG. 2 is a rear perspective view of the same;

FIG. 3 is an end view of the same; and

FIG. 4 is a top plan view of the same.

The center of the trim is broken away in the several views to indicate an article of indeterminate length.

I claim:

The ornamental design for a drip molding trim or the like, substantially as shown.
